**4-GAMMA-DIETHYLMINOPROPYLAMINO-
2:2:6:6-TETRAMETHYLPIPERIDINE**

Edwin Harry Paterson Young, Manchester, England, assignor to Imperial Chemical Industries Limited, London, England, a corporation of Great Britain
No Drawing. Filed Feb. 3, 1958, Ser. No. 712,624
Claims priority, application Great Britain Feb. 13, 1957
1 Claim. (Cl. 260—293)

This invention relates to new organic compounds and more particularly it relates to new piperidine derivatives which possess valuable therapeutic properties.

According to the invention we provide new piperidine derivatives of the formula:

wherein R stands for hydrogen or for an alkyl radical or an alkenyl radical of not more than 6 carbon atoms, optionally substituted, wherein R₁, R₂, R₃ and R₄, which may be the same or different, stand for methyl or ethyl radicals, and wherein the piperidine ring (A) may optionally be further substituted by a lower alkyl radical, a phenyl radical or a di-alkylamino-alkylamino radical, and the non-toxic pharmaceutically-acceptable acid addition salts and certain quaternary salts thereof.

It is to be understood that when the piperidine ring (A) contains no further substituents in positions 3, 4 or 5 then the substituents R, R₁, R₂, R₃ and R₄ together contain more than 4 carbon atoms.

It is further to be understood that by the expression "quaternary salts thereof" we include only those salts wherein the ring nitrogen atom is linked to two methyl radicals that is to say those compounds wherein R stands for a methyl radical and the ring nitrogen atom is further methylated.

As suitable optional substituents in the alkyl radical (R) there may be mentioned for example hydroxy, alkoxy and acyloxy substituents as illustrated by the β -hydroxyethyl, β -ethoxyethyl, β -acetoxyethyl and β -3:4:5:5-trimethoxybenzoyloxyethyl radicals.

As suitable non-toxic pharmaceutically-acceptable acid addition salts there may be mentioned for example the hydrochlorides, sulphates, phosphates, succinates, maleates, lactates and tartates and suitable quaternary salts 50 may be for example the methiodides.

Particularly valuable compounds of the above stated formula are 1-ethyl-2:2:6:6-tetramethylpiperidine, 1:2:2:6:6-pentamethylpiperidine, 1- β -acetoxy-ethyl-2:2:6:6-tetramethylpiperidine, 1- β -hydroxyethyl-2:2:6:6-tetramethylpiperidine, 1:1:2:2:6:6-hexamethyl-piperidinium iodide, 1-n-butyl-2:2:6:6-tetramethyl-piperidine, 1-allyl-2:2:6:6-tetramethylpiperidine, 2:6-diethyl-2:3:6-trimethylpiperidine and 2:2:6:6-tetramethyl-1- β -(3':4':5':5'-trimethoxybenzoyloxy)ethylpiperidine and of these, the preferred compound is 1-ethyl-2:2:6:6-tetramethylpiperidine.

According to a further feature of the invention we provide a process for the manufacture of certain of the new piperidine derivatives which comprises reduction of the corresponding compounds of the formula:

2

wherein R, R₁, R₂, R₃ and R₄ have the meaning stated above.

The said reduction process may be carried out by any means known to the art for example by the Clemmensen method by heating with amalgamated zinc and hydrochloric acid or by the Wolff-Kishner method by heating the corresponding hydrazone derivative with sodium or potassium ethoxide or with sodium or potassium hydroxide in the presence of an inert diluent or solvent for example di- or tri-ethylene glycol.

According to yet a further feature of the invention we provide a process for the manufacture of the new piperidine derivatives which comprises reduction of the corresponding tetrahydropyridine derivatives of the formula:

wherein R, R₁, R₂, R₃ and R₄ have the meaning stated above and wherein the tetrahydropyridine ring (B) may optionally be further substituted by a lower alkyl radical or by a phenyl radical.

The said reduction may be carried out by any means known to the art for example by the use of hydrogen and a catalyst for example Raney nickel or Adams' platinum oxide catalyst in the presence of methanol or by the use of sodium and ethanol.

The tetrahydropyridine derivatives used as starting materials may be obtained by dehydration of the corresponding 4-piperidols which may themselves be obtained either by reduction of the corresponding 4-piperidones or by treating the corresponding 4-piperidones with a Grignard reagent or with an acetylenic compound.

According to still a further feature of the invention we provide a process for the manufacture of those of the new piperidine derivatives wherein R is a radical other than hydrogen which comprises alkylation of a compound of the formula:

wherein R₁, R₂, R₃, R₄ and A have the meaning stated above.

The said alkylation process may be carried out by use of an alkyl halide or sulphate for example n-butyl bromide, allyl bromide or diethyl sulphate or an alkyl sulphonate for example methyl-p-toluene sulphonate. There may optionally be present an acid-binding agent for example excess of the piperidine base, lithium hydroxide or anhydrous potassium carbonate and there may optionally be present an inert diluent or solvent for example an excess of the piperidine base. Furthermore, when R stands for a methyl radical, the alkylation process may be carried out by the use of aqueous formaldehyde or a mixture of aqueous formaldehyde and formic acid and when R stands for a β -hydroxyethyl radical, the alkylation process may be carried out by the use of ethylene chlorohydrin.

According to a further feature of the invention we provide a process for the manufacture of those of the new piperidine derivatives wherein R stands for an alkyl radical containing a terminal acyloxy radical which comprises acylating the corresponding compounds wherein R stands for an alkyl radical containing a terminal hydroxy group.

Suitable acylating agents may be for example acid anhydrides for example acetic anhydride or acid halides for example 3:4:5-trimethoxybenzoyl chloride. The reaction may be carried out, if necessary, in the presence of an inert diluent or solvent for example benzene.

According to a further feature of the invention we provide a process for the manufacture of those of the new piperidine derivatives wherein R is an alkyl radical containing a terminal alkoxy substituent which comprises interaction of the corresponding compound wherein R is an alkyl radical containing a terminal halogen substituent and an alkali metal alkoxide for example sodium ethoxide.

The reaction may be carried out in the presence of the corresponding alcohol for example ethanol when the alkali metal alkoxide is sodium ethoxide.

According to a further feature of the invention we provide a process for the manufacture of those of the new piperidine derivatives which are quaternary salts which comprises methylating the corresponding tertiary bases wherein R stands for a methyl radical by known means.

The said quaternisation process may be carried out using a methyl halide for example methyl iodide preferably in the presence of an inert diluent or solvent for example acetonitrile.

According to a further feature of the invention we provide a process for the manufacture of those of the new piperidine derivatives wherein the piperidine ring (A) is further substituted in the 4-position by a di-alkylaminoalkylamino radical which comprises reductive alkylation of the corresponding 4-piperidone with a di-alkylaminoalkylamine in the presence of hydrogen and a platinum catalyst for example Adams' platinum catalyst.

As stated above the new piperidine derivatives and the non-toxic pharmaceutically-acceptable acid-addition salts and quaternary salts thereof possess valuable therapeutic properties and in particular they possess ganglion-blocking and hypotensive properties such as to render them of value in the treatment of hypertension. These compounds compare favorably with the known drug, mecamylamine, used in the treatment of hypertension. They may be used in combination with known drugs for example meprobamate, reserpine or aspirin. The bases and the acid-addition salts thereof are generally long-acting and are particularly suitable for the treatment of hypertensive disease while the quaternary salts are highly active and short-acting and are more suitable for controlled hypertension in surgical procedures.

The invention is illustrated but not limited by the following examples in which the parts are by weight:

Example 1

A mixture of 4 parts of 2:2:6:6-tetramethylpiperidine, 12 parts of 98% w/v. of aqueous formic acid and 15 parts of 38% w/v. of aqueous formaldehyde is heated gently under reflux for 8 hours. The solution is then cooled, made alkaline with aqueous sodium hydroxide solution and the mixture is extracted with 4 portions (35 parts each) of ether. The ethereal solution is dried, the ether evaporated and the residue is distilled to give 1:2:2:6:6-pentamethylpiperidine, B.P. 183-184° C./771 mm. It forms a picrate which may be crystallised from ethanol to give 1:2:2:6:6-pentamethylpiperidine picrate as a yellow crystalline solid, M.P. 274-276° C. with decomposition.

Example 2

A solution of 2.25 parts of 1:2:2:6:6-pentamethyl- $\Delta^{3,4}$ -tetrahydropyridine hydrochloride in 40 parts of methanol is shaken in an atmosphere of hydrogen with 0.5 parts of Adams' platinum oxide catalyst until the theoretical amount of hydrogen has been adsorbed. The reaction mixture is filtered and the filtrate is evaporated to about 5 parts. Ether is then added and after standing for a short time there is obtained the hydrochloride of

1:2:2:6:6-pentamethylpiperidine, M.P. 249° C. with decomposition.

The tetrahydropyridine used as starting material may be obtained by adding 1.2 parts of thionyl chloride to 4.27 parts of 4-hydroxy-1:2:2:6:6-pentamethylpiperidine in 45 parts of xylene and then heating the mixture at 98-100° C. for 3 hours. The xylene is distilled under reduced pressure and the residual syrup is crystallised from a mixture of ethanol and ethyl acetate to give 1:2:2:6:6-pentamethyl- $\Delta^{3,4}$ -tetrahydropyridine hydrochloride, M.P. 240-242° C. with decomposition.

Example 3

A mixture of 14.1 parts of 2:2:6:6-tetramethylpiperidine and 7.7 parts of ethyl sulphate is heated at 95-100° C. for 15 hours and is then cooled and diluted with 35 parts of ether. The mixture is filtered and the solid residue is washed twice with 20 parts of ether. The combined ethereal filtrates are evaporated and the residual oil is distilled and the fraction B.P. 188-198° C. at 760 mm. is collected. It is redistilled and there is thus obtained 1-ethyl-2:2:6:6-tetramethylpiperidine B.P. 194-198° C. at 760 mm. The base forms a picrate which when crystallised from ethanol has M.P. 245-247° C. with decomposition and a hydriodide which when crystallised from dilute aqueous hydriodic acid has M.P. 269-270° C. with decomposition.

Example 4

A mixture of 14.1 parts of 2:2:6:6-tetramethylpiperidine and 6.05 parts of allyl bromide is heated under reflux for 18 hours. 35 parts of ether are then added to the cooled mass and the mixture is filtered and the solid residue is washed twice with 35 parts of ether. The combined ethereal filtrates are evaporated and the residual oil is distilled and the fraction of B.P. 205-215° C. at 763 mm. is collected. It is redistilled and there is obtained 1-allyl-2:2:6:6-tetramethylpiperidine, B.P. 96-98° C. at 20 mm. pressure.

The base forms a picrate which when crystallised from ethanol has M.P. 162-163° C.

Example 5

A mixture of 14.1 parts of 2:2:6:6-tetramethylpiperidine and 6.84 parts of n-butyl bromide is heated under reflux for 96 hours. The mixture is filtered and the filtrate is distilled and the fraction B.P. 108-112° C. at 18 mm. is collected. It is redistilled and there is obtained 1-n-butyl-2:2:6:6-tetramethylpiperidine B.P. 96-98° C. at 12 mm.

The base forms a picrate which when crystallised from ethanol has M.P. 181-182° C.

Example 6

A mixture of 28.2 parts of 2:2:6:6-tetramethylpiperidine and 16.2 parts of ethylene chlorohydrin is heated in an oil bath at 155° C. for 3 hours. The mixture is cooled and an excess of 50% aqueous sodium hydroxide solution is added. The liberated base is extracted with four portions of 35 parts of ether and the ethereal extract is dried over anhydrous potassium carbonate and then evaporated. The residual oil is distilled and unreacted 2:2:6:6-tetramethylpiperidine distils at 40-60° C. at 12 mm. and can be retreated. The desired product, 1- β -hydroxyethyl-2:2:6:6-tetramethylpiperidine, distils as a colourless oil B.P. 140-142° C. at 12 mm. which solidifies on cooling and has M.P. 96° C. It forms a picrate which when crystallised from ethanol has M.P. 215-216° C.

Example 7

5 parts of acetic anhydride are added to 5 parts of 1- β -hydroxyethyl-2:2:6:6-tetramethylpiperidine and the mixture is heated gently under reflux for 1/2 hour. It is then cooled and poured into 20 parts of ice and excess of 40% aqueous sodium hydroxide solution is added. The mixture is extracted three times with 35 parts of ether and

the combined ethereal extracts are dried over anhydrous potassium carbonate and evaporated. The residual oil is distilled and there is thus obtained 1- β -acetoxyethyl-2:2:6:6-tetramethylpiperidine, B.P. 139-141° C. at 12 mm.

Example 8

4.61 parts of 3:4:5-trimethoxybenzoylchloride are added to a solution of 3.7 parts of 1- β -hydroxyethyl-2:2:6:6-tetramethylpiperidine in 22 parts of benzene and the mixture is heated under reflux for 1 hour. It is then cooled and filtered and the solid residue is washed with 8 parts of benzene and dried. It is then crystallised from ethyl acetate to give 2:2:6:6-tetramethyl-1- β -(3':4':5'-trimethoxybenzoyloxy) - ethylpiperidine hemihydrochloride, as a colourless crystalline solid, M.P. 157° C.

Example 9

4 parts of 1- β -chloroethyl-2:2:6:6-tetramethylpiperidine hydrochloride are added to a solution of sodium ethoxide prepared by dissolving 1 part of sodium in 200 parts of ethanol. The mixture is heated under reflux for 4 hours and is then cooled and filtered. The filtrate is concentrated by evaporation and 50 parts of water are added to the residue. The mixture is then extracted three times with 35 parts of ether. The combined ethereal extracts are dried over potassium carbonate and evaporated. The residual oil is distilled and there is thus obtained 1- β -ethoxyethyl-2:2:6:6-tetramethylpiperidine, B.P. 132-136° C. at 18 mm.

Example 10

5 parts of methyl iodide are added to a solution of 3.1 parts of 1:2:2:6:6-pentamethylpiperidine in 16 parts of acetonitrile and the mixture is heated under reflux for 3 hours. It is then cooled and filtered and there is thus obtained 1:1:2:2:6:6-hexamethylpiperidinium iodide, M.P. 210-211° C.

Example 11

10 parts of 4-ethyl-4-hydroxy-2:2:6:6-tetramethylpiperidine hydriodide are heated at 195-200° C. for $\frac{1}{2}$ hour and the resulting 4-ethyl-1:2:5:6-tetrahydro-2:2:6:6-tetramethylpyridine hydriodide is dissolved in 100 parts of water and excess of aqueous sodium hydroxide solution is added. The pyridine base is extracted with four equal portions of 70 parts of ether. The combined ethereal extracts are saturated with hydrochloric acid gas and the 4-ethyl-1:2:5:6-tetrahydro-2:2:6:6-tetramethylpyridine hydrochloride so obtained is dissolved in 40 parts of methanol and shaken in an atmosphere of hydrogen with 0.5 part of Adams' platinum oxide catalyst. When there is no further adsorption of hydrogen the reaction mixture is filtered and the filtrate is evaporated. The gummy residue is dissolved in 225 parts of ethyl acetate and the solution is filtered and evaporated to about 40 parts when there is obtained 4-ethyl-2:2:6:6-tetramethylpiperidine hydrochloride, M.P. 178° C.

The 4-ethyl-4-hydroxy-2:2:6:6-tetramethylpiperidine hydriodide used as starting material may be prepared as follows: A solution of 5 parts of 4-ethynyl-4-hydroxy-2:2:6:6-tetramethylpiperidine in 40 parts of methanol is shaken in an atmosphere of hydrogen with 0.25 part of Raney nickel catalyst until no more hydrogen is adsorbed (2 molecular proportions). The reaction mixture is then filtered and the filtrate is evaporated to give 4-ethyl-4-hydroxy-2:2:6:6-tetramethylpiperidine as an oil which solidifies on cooling and has M.P. 70-72° C. The hydriodide is obtained by crystallising the base from hydriodic acid. It has M.P. 195° C.

Example 12

A mixture of 5.5 parts of 4-keto-1:2:2:6:6-pentamethylpiperidine, 30 parts of triethylene glycol, 6 parts of hydrazine hydrate and 6 parts of potassium hydroxide is heated in an oil bath under reflux. The condenser is fitted with a take-off head so that water appearing in the

distillate can be removed. The internal temperature is gradually raised to 180° C. during 2 hours during which time water is drawn off from the distillate. The internal temperature is then raised gradually from 180° C. to 200° C. and the product 1:2:2:6:6-pentamethylpiperidine is collected. It is purified by distillation and has B.P. 182-183° C. at 768 mm. It forms a picrate of M.P. 274-276° C. with decomposition.

Example 13

10 A mixture of 10 parts of 2:6-diethyl-4-keto-2:3:6-trimethylpiperidine, 50 parts of triethylene glycol, 10 parts of hydrazine hydrate and 10 parts of potassium hydroxide is heated in an oil bath gently under reflux. The condenser is fitted with a take-off head so that water formed in the distillate can be removed. The internal temperature is allowed to rise slowly during the course of 1 hour from 120-200° C. The mixture is then cooled and poured into 500 parts of water and is extracted three times with 35 parts of ether. The combined ethereal extracts are dried and the ether evaporated and the oily residue is distilled. There is thus obtained 2:6-diethyl-2:3:6-trimethylpiperidine, B.P. 108-110° C. at 23 mm. It forms an acid oxalate which has M.P. 199° C. with decomposition after crystallisation from a mixture of ethanol and ethyl acetate.

Example 14

30 A mixture of 3 parts of 2:6-diethyl-2:3:6-trimethylpiperidine, 8.5 parts of formic acid and 10 parts of formalin (36%) is heated at 98-100° C. for 72 hours and is then cooled. An excess of 40% aqueous sodium hydroxide solution is added and the oily base is separated and the aqueous layer is extracted with 7 parts of ether. The combined ethereal extract and oily base is then dried over potassium hydroxide and the ether distilled. The residual oil is distilled to give 2:6-diethyl-1:2:3:6-tetramethylpiperidine, B.P. 119-121° C. at 18 mm.

Example 15

40 60 parts of zinc are allowed to stand for 1 hour in 120 parts of a 5% aqueous solution of mercuric chloride. The solution is then decanted and the amalgamated zinc is washed with water. 60 parts of a mixture of equal parts of water and concentrated aqueous hydrochloric acid (density=1.18) and 10 parts of 4-keto-1:2:2:6:6-pentamethylpiperidine are added to the zinc and the mixture is heated under reflux for 24 hours. During the first 5 hours, 5.9 parts of concentrated aqueous hydrochloric acid are added each hour to the reaction mixture. The mixture is then cooled and filtered. The solid residue is washed with a little water. The combined filtrates are made alkaline with excess of aqueous sodium hydroxide solution and the mixture is extracted twice with 70 parts of ether. The extract is dried and the ether is evaporated and the residue distilled. The fraction B.P. 172-186° C. is collected and redistilled. There is thus obtained 1:2:2:6:6-pentamethyl piperidine B.P. 183-184° C. at 771 mm. which forms a picrate identical with the product described in Example 1.

Example 16

45 A solution of 2 parts of 4-phenyl-2:2:6:6-tetramethyl- $\Delta^{3,4}$ -tetrahydropyridine hydrochloride in 40 parts of methanol is shaken in an atmosphere of hydrogen with 0.5 part of Adams' platinum oxide catalyst until no more hydrogen is adsorbed. The reaction mixture is filtered and the methanol is removed by evaporation under reduced pressure. There is thus obtained 4-phenyl-2:2:6:6-tetramethylpiperidine hydrochloride as a colourless solid 55 M.P. 225-226° C.

Example 17

60 A solution of 10 parts of triacetoneamine hydrate and 7.5 parts of gamma-diethylaminopropylamine in 80 parts of methanol is shaken with 0.5 part of Adams' platinum

oxide catalyst in an atmosphere of hydrogen until there is no further adsorption of hydrogen. The reaction mixture is filtered and the methanol is distilled. The residual oil is distilled under reduced pressure and there is thus obtained 4 - gamma-diethylaminopropylamino - 2:2:6:6-tetramethylpiperidine, B.P. 182-184° C. at 18 mm.

It forms a triplicate which when crystallised from ethanol has M.P. 212-214° C.

Example 18

37.2 parts of methyl p-toluenesulphonate are added with stirring to 28.2 parts of 2:2:6:6-tetramethylpiperidine. 10 parts of lithium hydroxide monohydrate are then added and the mixture is allowed to warm spontaneously. After 1/2 hour the mixture is heated at 100° C. for 2 hours and then 100 parts of water and 25 parts of 40% aqueous sodium hydroxide are added. The oily layer is separated and distilled when there is obtained 1:2:2:6:6-pentamethylpiperidine which boils at 182-185° C. at 763 mm. pressure.

Example 19

A mixture of 28.2 parts of 2:2:6:6-tetramethylpiperidine and 20 parts of ethyl p-toluenesulphonate is heated on a steam bath for 24 hours. It is then cooled to 25° C. and made alkaline by the addition of 50 parts of 40% aqueous sodium hydroxide solution and extracted with 105 parts of ether divided into three equal portions. The ethereal extract is dried over potassium hydroxide and the ether is then distilled. The residual oil is fractionated and there is thus obtained 1-ethyl-2:2:6:6-tetramethylpiperidine, B.P. 193-197° C. at 740 mm.

What I claim is:

A piperidine selected from the group consisting of 4 - gamma-diethylaminopropylamino-2:2:6:6-tetramethylpiperidine and the non-toxic pharmaceutically-acceptable acid addition salts thereof.
